United States Patent Office.

W. SMITH, OF SAN FRANCISCO, CALIFORNIA.

Letters Patent No. 91,574, dated June 22, 1869.

IMPROVEMENT IN WATER-CLOSET VALVES.

The Schedule referred to in these Letters Patent and making part of the same.

To all whom it may concern:

Be it known that I, W. SMITH, of San Francisco, in the county of San Francisco, and State of California, have invented certain new and useful Improvements in Valves for Water-Closets; and I do hereby declare that the following is a full and exact description of the same, reference being had to the accompanying drawings, and to the letters of reference marked thereon.

This invention relates to a new and useful improvement in valves for water-closets, and is suitable for either pan or hopper-closets, whereby they are rendered more useful and durable than they have hitherto been; and

It consists in the construction and arrangement of parts, as hereinafter described.

The drawing represents a vertical longitudinal section of the valve as applied to a pan-closet.

A represents the shell of the valve, formed of different sections, together with packing secured in the joints, and is fastened to a projecting arm, B, cast on the receiver for that purpose, as seen in the drawing.

C is an extension-screw on the spindle E, which is depressed by the arm F of the closet-lever, which has its fulcrum at c.

In this manner the spindle E is depressed, and with it the tube D, which bears on the inner packing e of the valve f, and drives the spindle G, with the plunger H, into the chamber I.

While the valve is in this position, no water can pass through it.

When the pull of the closet is dropped, the spring J lifts the spindle E and tube D from the packing e, when the water flows through the tube D and waterways K K, at its upper end, and through the outlet-pipe L to the basin, which it washes, and leaves the pan full, ready for use again.

The stem K' of the valve f, extends upward through the tube D, and has a head on it, that fits, and allows it to slide in the recess M at the top.

By this arrangement, a slip-connection is made between the spindles E and G, which admits of the tube D being lifted from the packing e a sufficient distance to allow the water to pass through the tube, as previously described.

The plunger H, having been depressed or forced into the chamber I, would be drawn upward by the spring J, but for the following reasons:

The chambers N and I being filled with water, the descent of the plunger H causes the water to escape past the elastic washer o, to the upper chamber N.

Now, before the valve and plunger can ascend again, to close the valve, the displaced water, now occupying the chamber N, must return to the lower chamber I; but this is prevented by the elastic washer o, and the water is retained in the chamber, except as it escapes through a vertical channel cut in the side of the plunger, marked p, which permits the water to return

gradually, thereby suspending the valve a sufficient length of time to give the requisite wash to the basin.

The valve f, when closed, bears against the packing g.

The length of time the water is allowed to wash depends on the stroke of the valve, which is adjusted by the screw C.

Between the partition g and the packing q there is an annular upright strainer, u u, to admit of which the shell of the valve in that portion is enlarged, which forms a jacket or water-passage, v v, to give the water access to the entire surface of the strainer; and by placing it in this manner, I have the benefit of a large surface.

By this improvement, impediments in the water, such as sand and gravel, are prevented from getting under the valve-face, and causing it to leak—a source of great trouble in ordinary water-closet valves.

The packing q is fitted tightly around the tube D, and prevents any leakage around the tube while the valve is depressed.

To prevent leakage, the upper portion of the tube D is surrounded by a tightly-fitted washer, secured in the screw-joint, as seen at R in the drawing.

h is a waste-outlet, to carry off any leakage that may escape past the washer R.

The face of the tube D is always in such a position with the valve f, that the pressure of the water alone would close it, if the spring were not present to keep the tube raised from its seat until the valve closes against the packing q.

It will be seen that the principal improvement in this valve consists in having the tube D and valve f so constructed, that should the spring become defective, the valve will remain closed, and allow no water to pass, and under no circumstances can it be fastened open, either by accident or design.

In applying this valve to hopper-closets, I make use of the flange Y, which is fastened to the floor in the usual manner; and the adjustable socket X is used instead of the screw C. A rod extends from the socket to the seat of the closet, which is hinged, and yields to the weight of the person, and operates the valve in the same manner as previously described.

Having thus described my invention,

What I claim as new, and desire to secure by Letters Patent, is—

The sliding tube D, having ports K K and recess M, in combination with the stem K', having a head, a, fitted to slide in the recess M, to form a slip-joint, substantially as described.

In witness whereof, I have hereunto set my hand and seal.

W. SMITH. [L. S.]
